QUENCHING MACHINE

John Joseph Davenport, College Point, Long Island, N. Y., assignor to James I. Quaid, College Point, Long Island, N. Y.

Application September 14, 1937, Serial No. 163,874

1 Claim. (Cl. 266—6)

This invention relates to quenching machines and an object of the invention is to provide a machine of this character whereby the heat treating of all kinds of tools and dies for the hardening and annealing of the same is greatly simplified; and further to provide such a machine which may be easily operated by an unskilled workman.

A further object of the invention is to provide a machine of the character above mentioned for the heat treatment of steel dies whether the latter be of carbon steel, alloy steel or tungsten steel.

The invention together with its objects and advantages will be best understood from a study of the following description taken in connection with the accompanying drawings wherein:

Figure 1 is an elevational view of the machine with parts broken away and shown in section.

Figure 2 is a vertical sectional view taken substantially on the line 2—2 of Figure 1, and

Figure 3 is a top plan view of a lower form member.

Referring to the drawings by reference numerals it will be seen that in the preferred embodiment thereof the quenching machine comprises a stand or table 5 of any suitable construction and the same is provided on the top thereof with rails 6, 7.

The rail 6, in the present instance, and as clearly shown in Figure 2, is in the form of a single angle iron while the rail 7 is in the form of a pair of relatively spaced angle irons.

Rideable on the rails 6 and 7 is a carriage 8 in the form of a frame. To the under face of one side member of the frame 8 is secured by screws 35 or other fastening elements 9 a wear plate 10 that engages the rail 6. To the under face of an opposite side member of the carriage 8 is a wear plate 11, of angle iron structure and having one flange thereof secured to the frame through the medium 40 of fastening elements 12 while the other flange of said wear plate is accommodated between the upstanding flanges of the angle iron plates of rail 7 as also clearly shown in Figure 2.

Suitably mounted on the carriage 8 is a base plate 13 from which rises a bracket 14 that is provided in the upper end thereof with a bearing 15 in which is snugly fitted an internally threaded bushing 16 provided at its upper end with a flange 17 as shown.

Threading through the bushing 17 is an adjusting screw 18 that is provided on its upper end with a hand wheel 19.

Swivelly connected with the lower end of the screw 18 in any suitable manner and as indicated generally at 20 is a top form 21 which consists of

a casting of metal or other suitable material externally tapered as at 22 and provided with a conical bore 23 whereby at the largest or outlet end of the bore 23 is presented a sharp edge 24 that has bearing contact with the steel die 25 to be hardened.

The plate 13 in substantial alignment with the bearing 15 is formed to provide a well 26 merging into a guide extension 27.

Cooperable with the form 21 is a second form 28 provided on the upper end of a tubular stem 29 that extends through the well 26 and has a working fit in the bore of the guide 27.

Accommodated within the well 26 is a coil spring 30 that at its upper end bears against the form 28 for yieldably urging the latter upwardly to remain in constant contact with the lower face of the die 25 as the die contracts during the quenching or hardening of the material of the die 25.

The form 28 is also provided with a sharp edge 31 that engages against the die 25 and said edge 31 is formed by tapering the upper portion of the form as at 32, externally, and by providing a dished-out recess 33 in said upper portion of the form 28. Also a bore or hole 34 extends through the form 28 from the bottom of the recess 33 to the stem 29 and in alignment with the bore of the stem.

Also the form 21 is provided with a lateral intake passage 35 that is connected through the medium of piping 36 with the lateral outlet of a liquid receiving cylinder 37 that moves vertically with the form 21. The flow of liquid from the cylinder 37 to the form 21 is controlled through the medium of any suitable valve 38 arranged in the pipe line 36.

At the top thereof the cylinder 37 is provided with a gland 39 that accommodates a feed tube 40 connected as at 41 with the outlet 42 of a pump 43.

Pump 43 is driven from an electric motor 44 and said pump 43 and motor 44 are mounted on a base 45 bolted or otherwise secured as at 46 to a ledge 47 suitably provided on the standard or bracket member 14.

To the inlet side 48 of the pump 43 there is coupled one end of a pipe 49 that has a hose section 50 connected therewith and adapted to extend into a selected one of tanks 51, 52, 53.

In connection with the tanks it will be understood that with this machine either water in tank 51 or a special hardening compound in tank 52 or a quenching oil in tank 53 may be used for treating and hardening the work or die 25.

The operation and utility of the invention will be apparent from the following:

The hot die 25 is placed on the form 28 after which the screw 18 is fed downwardly to engage the form 21 with the top of the die 25 to clamp the die 25 between the forms 28 and 21.

5 Pump 43 driven by the motor 44 is then set into operation and with the pipe extension 50 arranged in a selected one of the tanks 51, 52 or 53 the liquid contents of the selected tank is drawn therefrom and fed through the tube 40 to the cylinder 37. The liquid passes from the cylinder 37 through the piping 36 into the form 21 and passes from the form 21 through the bore in the die 25 to cool and consequently harden the die. The liquid passing through the bore of the die 25 10 continues downwardly through the aperture 34 in the form 28 and the bore of the stem 29 to return to the tank from which it was drawn.

It will be seen that as the die 25 cools and contracts spring 30 will expand to maintain the 20 edge 31 of form 28 in contact with the die 25 and at the same time an upward pressure is exerted on the die to maintain the upper face thereof in engagement with the edge 24 of the form 21. As a result the contact between the form 21 and the die 25 on the one hand and between the form 28 25 and the die 25 on the other hand will be such as to preclude, at all times, any escape of liquid at the points of contact between the die and the form.

30 In connection with the above it will be understood that the edges 24 and 31 of forms 21 and 28 are in constant contact with the die 25 so that the liquid will flow through the member 22 and then through the die 25 into the bowl 33 of member 28 and will then pass through the conduit 34 and tube 29 back into a tank. Of course, all 35 those portions of the die contacted by the liquid will be hardened, as shown in the shaded part at the center of the die in Figure 2.

40 It will also be appreciated that the carriage 8 may be readily shifted along the track rails 6 and 7 to be properly positioned over a selected tank 51, 52 or 53.

It is thought that a clear understanding of the construction utility and advantages of this invention will be had without a more detailed description.

Having thus described the invention what is 5 claimed as new is:—

A device for treating dies having passages therein comprising a base plate having an opening therein and a depending part of tubular construction forming a continuation of the opening and said depending part terminating in a tubular guide, a lower form having a chamber therein opening out through the top of the form, a tubular stem connecting with said form and in communication with the chamber thereof and passing through the opening and the depending member and having its lower part slidably arranged in the guide, a spring in the opening and the depending part and having its upper end bearing against the under part of the form and its lower end against the bottom of the depending member, a bracket rising from the base plate and having a vertically arranged screw-threaded opening in its upper end in vertical alignment with these forms, a screw shaft passing through the opening, an upper form swivelled to the lower end of the shaft and having a chamber therein opening out through the lower end of the form, the upper form being in vertical alignment with the lower form and the two forms receiving between them a die to be treated, a vertically arranged tank, a horizontally arranged pipe connecting the tank with the upper form, said pipe being in communication with the chamber of the upper form, a pump carried by the bracket and a vertically arranged pipe connected with the discharge of the pump passing into the tank through the top thereof, said top of the tank having a sliding fit on said pipe, the lower form having a flat underface for engaging the upper face of the base plate when the lower form is in lowered position.

JOHN JOSEPH DAVENPORT.
